UNITED STATES PATENT OFFICE.

ROY M. HALL, OF VALPARAISO, INDIANA.

REPLACEABLE MEMORANDUM PAD.

Application filed March 6, 1924. Serial No. 697,334.

My invention relates to improvements in replaceable memorandum pads and it consists more especially of the features hereinafter pointed out in the annexed claims.

5 The purpose of my invention is to provide a monthly replaceable memorandum pad that can be readily and authentically identified, as to the year, the month, day of month and day of week; that can be assembled in 10 any desired type or style of cover; and that serves as a source of reference of past appointments, memoranda, etc., etc., when filed away month by month.

With these and other ends in view 15 I illustrate in the accompanying drawing such instances of adaptation as will disclose the broad underlying features without limiting myself to the specific details shown thereon and described herein.

20 Fig. 1 is a front elevation impartial perspective of my pad.

Fig. 2 is a rear elevation of Fig. 1.

Fig. 3 shows the pad in assembled relation in a holder.

25 This present invention is an important improvement over pads of this class made heretofore. It is extremely simple and yet remarkably effective in practice. The outstanding features are instanced in

30 Fig. 1. At the top of the pad is printed a series of consecutively numbered years, and the legend "Month of ____ 192____." The series of years is usually made up in groups of five and the annual printings drop the oldest year at the left and add the latest year on the right. Each sheet bears this inscription. At the bottom of the sheet the days of the week "Sun. Mon. Tues. Wed. Thurs. Fri. Sat." on each 35 sheet and a changing numeral representing the day of the month. There are thirty-one sheets in a pad as a minimum, the first one being numbered "1", the next "2" etc., throughout the month.

40 In use the desired memorandum or appointment is noted in the blank space of the sheet corresponding to the day of the month on which the entry is made, then the corresponding year and day of the week is checked, as shown in Fig. 1, on which there is checked the year "1924", the day of the week "Fri." and the month "February" is written in on the 1st of the month.

The sheets of a pad are assembled in consecutive order as single numerals or they may be grouped two or three sheets of the

same number so as to increase the capacity of the pads. They are held together by staples or otherwise. The sheets are identified by the numeral 1, the years by 2, the "month of" by 3, the days of the week by 4 and the day of the month by 5. A flap 6 on the back slips into a pocket formed on the inside of one of the covers 7. I have adopted an identifying slogan "Lest we forget" which is usually printed on the front of the cover and may also be printed on the inside of the cover above the slip-in pad 8.

My improved form of pad possesses many 70 advantages over pads which only carry "Month of ____ 192____" and a numeral on each sheet representing the related day of the month because every item entered on a sheet is immediately authenticated as 75 to date. In addition, the pad has great merit as an advertising medium for banks, etc. They are sold in sets of twelve with a cover for the set. Banks, etc., distribute a cover and a single pad to a customer 80 with the promise of a new pad for each succeeding month. This brings the recipient of the favor back to the place of business twelve times in a year—an important 85 advantage in any line of business.

What I claim is:

1. In replaceable memorandum pads, a group of sheets constituting a supply for a single month, each sheet having printed thereon in consecutive order numerals representing the days of the month, an appropriately designated space for the month and year, a series of numerals representing a group of consecutive years, the days of the week, means for holding the sheets 90 in assembled relation, and a suitable flap adapted to removably hold the pad in a protective cover.

2. In replaceable memorandum pads, a group of sheets constituting a supply for 100 a single month each sheet having printed thereon numerals in consecutive order representing the days of the month, a designated space for the month and year, a plurality of consecutively numbered years, and 105 means for holding the sheets assembled at one edge.

3. In replaceable memorandum pads, a group of sheets constituting a single month's supply each sheet having printed thereon 110 numerals representing the consecutive days of a month and each of the seven days of

a week, an appropriately designated space for the month and year, and means for holding the sheets in assembled relation so that the days of the month will follow each other

5 in numerical sequence.

4. In replaceable memorandum pads, a plurality of separate sheets having printed thereon a series of years, a list of the days of the week, an appropriately designated

10 space for the month and year, and separate

value numeral sheets, means for holding the sheets permanently assembled so the numerals will follow each other in an ascending order sequence, and a flap in common to all the sheets adapted to hold the memorandum 15 in a suitable holder.

In testimony whereof I affix my signature.

ROY M. HALL.
